UNITED STATES PATENT OFFICE.

ALBERT E. HOADLEY, OF CHICAGO, ILLINOIS.

CAR BRAKE AND STARTER.

SPECIFICATION forming part of Letters Patent No. 238,588, dated March 8, 1881.

Application filed June 26, 1880. (No model.)

To all whom it may concern:

Be it known that I, ALBERT E. HOADLEY, a citizen of the United States, residing at Chicago, in the county of Cook and State of Illinois, have invented a new and useful Improvement in Combined Car Brakes and Starters, of which the following is a specification.

My invention relates to an improvement in the mode of using the momentum of the car 10 as a force to start it by raising the body of the car while stopping, and starting the car by letting the weight of the body fall, so as to turn the axles of the car.

My invention is an improvement on a former 15 invention by me in car brakes and starters secured to me by Letters Patent of the United States No. 229,041, dated June 22, A. D. 1880.

My improvement consists in placing the eccentric friction-wheels, by which the body of 20 the car is raised, outside of the car-wheels and raising the springs of the car with the body, thus preventing any rough or unpleasant sensation to those in the car, and also in a new and improved mode of constructing and applying 25 the friction-wheels.

Figure 1 is a sectional view of one of the car-wheels and eccentric friction-wheels. Fig. 2 is a face view of one of the eccentric friction-wheels and car-wheel with springs, yoke, and 30 binding-lever. Fig. 3 is a view of the rods, levers, and spring, by which the friction-wheels are applied to the car-wheels.

Similar letters refer to similar parts throughout the several views.

The mode of operation is as follows: The 35 rods S S, Fig. 3, are attached to the brake-rods (one of which is at each end of the car in ordinary use on street-railways) by a short chain, only one being in use at a time. When 40 the brakes are applied by the driver, the rod S draws upon the lever i, which, in turn, draws the rods l l and compresses the spring J, drawing the rods K K, attached to equalizing-levers h h, which are attached by links t t to the 45 levers F F, respectively, the other end of each lever F being attached to the rod N, connecting the levers on opposite sides of the car. Each lever F passes around the axle of the car, outside of the car-wheel and eccentric friction-wheel C, and is attached by pins to a hub or collar, which moves freely on the axle A. (See Figs. 1 and 2.) When the brake is ap-

plied the lever F presses the eccentric friction-wheel C against the car-wheel B.

The eccentric friction-wheel C is constructed 55 with the longest radius about four inches longer than the shortest, but with the inner surface, I I, prolonged and circular, (see Fig. 1,) and constructed so that it is only applied to the car-wheel upon the beveled surface x x, near 60 the periphery of the latter. (See Fig. 1.)

In that part of the eccentric wheel which is above the axle of the car while in motion, and the eccentric wheel not applied to the car-wheel, is a chamber, b, Fig. 1, for holding oil, 65 which passes through an opening at the lower extremity to the axle.

The four eccentric wheels are constructed and operate in the same manner and at the 70 same time.

Extending over the eccentric wheel C is a yoke, D, upon the extremities of which rest the car-springs g g, and through which the spring-bolts f f pass. (See Fig. 2.) In this yoke is a loose pulley, E, (see Figs. 1 and 2,) which 75 rests upon the eccentric wheel C. Upon the outer face of the latter is a flange, a, (shown in Fig. 2 by the dotted line a.) This prevents the pulley rolling off the eccentric wheel, and also, when the eccentric friction-wheel is applied to the car-wheel, tilts the yoke D, the ends of which, being bound down by the car-springs g g, act to bring the eccentric wheel 80 back to place again when the pressure is relieved.

When the eccentric friction-wheel C is pressed against the car-wheel by the action of the driver turning the brake, as heretofore shown, the eccentric wheel, being loose on the axle, commences to revolve, and as its longest radius 90 approaches the pulley E the car gradually rises. When the lug p on the periphery of the eccentric wheel strikes the pulley E, the eccentric friction-wheel must either slip on the car-wheel or the car-wheel slip on the track 95 until the car stops, depending upon the amount of force exerted by the driver. As the eccentric friction-wheel C revolves, the lug p strikes the ends of the rods e or e', passing through the yoke D, and raises them, the rods e and e' being constructed and operating the same, and for the same purpose, as the rods w and w' in Fig. 1 of specification to Letters Patent 100 heretofore referred to—No. 229,041. When

the brake is released the levers F F are thrown back by the spring J and by the springs of the car, bringing the yoke D back to its vertical position, as heretofore shown, and the 5 weight of the car is thrown upon ratchet-wheels, and the car started in the manner described in the specification to said Letters Patent No. 229,041.

Extending over the face of the eccentric 10 wheel is an iron plate, o, (shown by the broken and dotted line o in Fig. 2,) which is firmly attached to the beam H of the car, Figs. 1 and 2, and is bent under the springs g and g at the corners of the plate, and receives the 15 spring bolts or rods f and f, respectively.

At the extremity of the axle of the car is a cap, e, Figs. 1 and 2, in which the end of the axle revolves. Said cap rises and falls in the 20 slot d in the iron plate o, as shown by the dotted line in Fig. 2. This holds the car vertically over the axles. From the circumference of the axle to its extremity is an opening, r, Fig. 1, for the passage of oil to lubricate the extrem-

ity of the axle in the plate e, and also lubricate the slot d for the plate e.

What I claim is—

1. The combination of the lever i, the rod l, the spring J, the rod K, the lever h, and the levers F, for the purpose specified, all arranged substantially as set forth.

2. The eccentric friction-wheel C, containing oil-chamber b, with its inner surface prolonged and circular, working against the beveled surface x of the car-wheel, for the purpose specified, substantially as set forth.

3. The yoke D, containing pulley E, for the purpose specified, substantially as set forth.

4. The plate o, provided with the slot d, in combination with the plate e, working in said slot and upon the end of axle A, substantially as described, for the purpose specified.

ALBERT E. HOADLEY.
